UNITED STATES PATENT OFFICE

SAMUEL B. HALL, OF BROOKLYN, NEW YORK, ASSIGNOR TO REMINGTON TYPEWRITER COMPANY, OF ILION, NEW YORK, A CORPORATION OF NEW YORK

TYPEWRITING MACHINE

Application filed November 28, 1927. Serial No. 236,196.

My invention relates to typewriting machines and more particularly to so-called dust guard means which will prevent particles of grit or rubbings that drop from the front face of the platen and pass to the rear of the type bar segment from entering the pivot bearings of working parts of the machine.

The object of my invention, generally stated, is to provide simple, inexpensive and highly effective means of the character specified which may be readily incorporated in existing machines without modifying, or materially modifying, the existing structural features thereof.

To the above and other ends which will hereinafter appear, my invention consists in the features of construction, arrangements of parts and combinations of devices set forth in the following specification and particularly pointed in the appended claims.

In the accompanying drawings, wherein corresponding reference characters designate corresponding parts in the different views,

Fig. 1 is a detail, vertical, fore and aft, central sectional view showing a portion of a typewriting machine equipped with the dust guard of my invention;

Fig. 2 is an enlarged, detail, fragmentary, top plan view showing one end portion of the type bar segment and dust guard and some of the associated parts;

Fig. 3 is a top plan view of the blank from which the dust guard is formed; and

Fig. 4 is a detail, fragmentary, perspective view, as seen from the rear, of the type bar segment, the dust guard, and some of the associated parts.

The invention is shown in the present instance embodied in a No. 12 Remington machine in which said invention may be readily included without modifying, or materially modifying, the structural features of said machines as they now exist. Only so much of said machine is shown as is necessary to arrive at an understanding of my invention in its embodiment therein. It should be understood, however, that the invention is not restricted to embodiment in the machine re-

ferred to, but may be used in various styles of typewriting machines, wherever found available.

In the drawings, 1 represents the platen which is diagrammatically illustrated and is carried by the carriage (not shown) to travel from side to side of the machine over the usual top plate 2 of the machine.

Each type action of the machine comprises a key lever 3 pivoted at 4 to a sub-lever or actuating member 5. Each sub-lever is pivotally supported on a pivot wire 6 and works in a guide slot 7 of a casting or support 8 which extends across the machine and is secured at its ends by screws 9 to the base portion of the frame, not shown. The upright arm of each sub-lever 5 carries a headed pin 10 which works in a slot 11 in the heel of the associated type bar 12. These type bars are mounted to turn on a pivot wire 13 carried by an upright type bar segment 14 provided with radial guide slots 15 in each of which the heel of a type bar works and is guided. The rear side of the segment 14 has a segmentally disposed channel 16 located above the heels of the type bars, and in which is located the usual segmental universal bar 17 that works fore and aft of the machine under control of the cams 18 on the heels of the type bars.

Extending inward from each side of the central opening in the top plate is a supporting member or lug 19 and to which the type bar segment is secured by screws 20. The upwardly and rearwardly swinging type bars, which impact against the front face of the platen, are guided by a center guide 21 secured by screws to the front face of the segment.

The construction, as thus far described, constitutes part of the No. 12 Remington machine, and I will now describe the features of my invention which are combined therewith.

The pivot bearings of the type bars and the sub-levers are protected in the usual construction against the admission of falling particles of grit, etc., that may drop from the front of the platen forward of the type bar segment. In this connection it will be

observed that a dust guard 22 on the front face of the segment, overlies the bearing slots 15 of the type bar segment. Therefore, the present invention is directed more particularly to means for preventing particles that drop from the platen to the rear of the segment from entering, not only the pivot bearings for the type bars, but the pivot bearings of the sub-levers as well, which latter feature has proved to be an important factor.

The dust guard 23 is formed from a strip of resilient metal or half hard spring stock, and a blank from which the dust guard is formed is shown in Fig. 3. It will be seen that about midway in the length of this strip there is provided in the rear edge thereof a cutout or aperture 24 to receive a part of an actuating member (not shown) for the ribbon vibrator.

Each end of the strip has its edge beveled or cut off at an angle to the adjacent dotted line *a*, as represented at 25. These lines *a* represent the lines where the end portions 25 of the strip are bent off at an angle to the main body portion thereof to provide blade-like supporting ears 26. Each lug 19 on the top plate has its inner side cut through from front to rear to provide a bearing slot 27 (see Fig. 1) in which one of the supporting ears 26 is received and seated. Each of these slots, as viewed in Fig. 1, is preferably inclined slightly to the horizontal, say to the extent of from two to five degrees, depending 35 somewhat on conditions and the character of the stock employed. In the present illustration such inclination is shown as about five degrees, mainly for the purpose of clearly illustrating this feature. Otherwise stated 40 the plane of each slot 27 is slightly less than a right angle to the plane of the type bar segment when the latter is secured in place. The effect of supporting the dust guard in this manner at the ends thereof is to maintain 45 the forward contact edge of the dust guard, especially at the lower central portion thereof, snug against the rear side of the segment. It will be understood that there is, by this arrangement, a straining of the ears in the 50 slots 27 which tends to force the lower bowed central portion of the dust guard forward against the rear side of the segment, and that this same straining of the ears in the slots tends to create a binding action of the ears 55 against the walls of the slots to hold the dust guard against accidental displacement therefrom. Before the segment has been mounted in place the dust guard is bent by hand against the inherent force of its spring 60 to a curved condition, and while it is thus held, the guard is introduced in place from the front of the machine with the ears in the bearing slots. The ears are forced rearwardly a part of the distance they are finally to 65 assume in the slots with the lower end por-

tion of the dust guard extending forward into the path of the segment when the latter is introduced into position. As the segment is placed and secured in position this will tend to strain the lower portion of the guard 70 rearward and also displace the ears 26 to their home position in the slots so that the entire front edge of the dust guard will lie snug against the rear side of the segment, as shown in Fig. 1; the straining of the 75 metal, however, tending to maintain the lower middle portion against the segment with the greatest assurance. From an inspection of Fig. 2 it will be understood that the bottom wall 28 of each slot 27 is inclined inward from front to rear to match the inclination of the end 25 of ear 26 to be received therein. The extent of the inclination of each wall 28 and each end 25 is exaggerated in the drawings for the purpose 80 of clearly illustrating this feature. However, the extent of such inclination may vary under different conditions. It will be understood that the reaction of the spring of the dust guard will tend to seat each inclined end 25 against the correspondingly inclined wall 28 of the slot 27 in which it is received, and that such coacting inclined surfaces and said force will tend to cam the dust guard forward and resist its rearward displacement and thus keep the front edge of the dust guard in close contact with the rear side of the segment.

It will be seen that the dust guard extends rearward from the segment a sufficient distance to cover the rearwardly projecting portion of the universal bar, the heels of all of the type bars, the connections between all of the sub-levers and type bars and the pivot bearings of all of the sub-levers, which latter feature is highly important.

It will be understood from the foregoing that it is the reaction of the spring force of the dust guard which tends to hold the latter in the position in which the guard is placed; that the cramping action of the ears 26 in the slots 27 and the cam surfaces 25 and 28 insure the maintenance of the forward edge of the dust guard in contact with the rear side of the segment and prevent an accidental creeping of the dust guard from its effective position when the machine is in use. The construction is such, nevertheless, that the dust guard may be readily sprung into place or detached when desired.

It will be seen, moreover, that the construction is inexpensive and may readily be embodied in the No. 12, as well as other models of, Remington machines without modifying the structural features thereof further than to cut saw-kerfs in the lugs 19 to form the slots 27.

Various changes may be made in the construction, and certain features thereof may be employed without others, without depart-

ing from my invention as it is defined in the accompanying claims.

What I claim as new and desire to secure by Letters Patent, is:—

1. The combination of an upright type bar segment, a series of type bars pivoted thereto, and a dust guard that projects rearward from the rear face of said segment above the pivot bearings of said type bars, said dust guard being formed from a strip of spring metal that is sprung into place for use and held fast in effective position by its inherent spring force.

2. The combination of an upright type bar segment, a series of type bars pivoted thereto, and a dust guard located wholly in the rear of the segment and that projects rearward from the rear face of said segment above the pivot bearings of said type bars and is retained in such position during the operation of the type bars, said dust guard being formed from a strip of metal with supporting ears provided at the ends thereof, and a support for said dust guard having slots in which said ears are removably seated by a sliding action of the ears in said slots.

3. The combination of an upright type bar segment, a series of type bars pivoted thereto, a dust guard that projects rearward from the rear face of said segment above the pivot bearings of said type bars, said dust guard being formed from a strip of spring metal with supporting ears provided at the ends thereof, and a support for said dust guard having slots in which said ears are seated and held by the reaction of the spring force of said dust guard.

4. The combination of an upright type bar segment, a series of type bars pivoted thereto, a dust guard that projects rearward from the rear face of said segment above the pivot bearings of said type bars, said dust guard being formed from a strip of spring metal with supporting ears provided at the ends thereof, said ears having outer beveled or inclined edges, and a support for said dust guard having slots in which said ears are seated and held by the reaction of the spring force of said dust guard, the bottom wall of each of said slots being sloping to match the beveled edge of the ear that is received therein, said sloping walls and beveled edges on the ears tending to prevent the dust guard from working away from the rear side of the segment.

5. The combination of an upright type bar segment, a series of type bars pivoted thereto, a dust guard that projects rearward from the rear face of said segment above the pivot bearings of said type bars, said dust guard being formed from a strip of spring metal with supporting ears provided at the ends thereof, and a support for said dust guard having slots in which said ears are removably seated, the plane of each of said slots

being slightly less than a right angle to the plane of the segment, whereby when the ears are seated in said slots the lower portion of the dust guard will be forced to bear snugly against the rear side of the segment and said ears will receive a slight binding action against the walls of said slots.

6. The combination of an upright type bar segment, a series of type bars pivoted thereto, a dust guard that projects rearward from the rear face of said segment above the pivot bearings of said type bars, said dust guard being formed from a strip of spring metal with supporting ears provided at the ends thereof, said ears having outer beveled or inclined edges, and a support for said dust guard having slots in which said ears are seated and held by the reaction of the spring force of said dust guard, the bottom wall of each of said slots being sloping to match the beveled edge of the ear that is received therein, said sloping walls and beveled edges on the ears tending to prevent the dust guard from working away from the rear side of the segment, the plane of each of said slots being slightly less than a right angle to the plane of the segment, whereby when the ears are seated in said slots the lower portion of the dust guard will be forced to bear snugly against the rear side of the segment and said ears will receive a slight binding action against the walls of said slots.

7. The combination of an upright type bar segment, a series of type bars pivoted thereto, a series of pivoted sub-levers, and a dust guard formed from a strip of resilient metal adapted to be bent into a curved condition and retained seated on its support and in a curved condition by the reaction of the resilient strip, said dust guard extending from the rear face of the segment and overlying the heels of the type bars and protecting the pivot bearings of the type bars and the sub-levers as well from rubbings or falling particles which drop from the front face of the platen to the rear of the segment.

8. The combination of an upright type bar segment, a series of type bars pivoted thereto, a series of type bar actuating members pivoted below the heels of the type bars, a dust guard formed from a strip of resilient metal adapted to be bent into a curved condition and having bent-off securing or supporting blades, and a support to which the segment is detachably secured and which is provided with slots in which said securing blades are received and held seated by the resiliency of said strip and to hold the strip in a bent condition over the heels of the type bars and extending from the rear side of the segment and protecting the pivot bearings of the type bars and of the actuating members as well from rubbings or falling particles which drop from the front face of the platen to the rear of the segment.

9. The combination of an upright type bar segment, a series of type bars pivoted thereto, and a dust guard formed from a strip of resilient metal adapted to be bent into a curved condition and detachably held in fixed position of use and in association with said segment by the inherent resiliency of said strip.

5 Signed at the city of New York, in the county of New York and State of New York,
10 this 26th day of November A. D. 1927.
